GEORGE H. MESSER, OF NEWARK, NEW JERSEY.

OIL-SUPPLY-CONTROLLING APPARATUS FOR LIQUID-FUEL BURNERS.

Application filed April 6, 1926. Serial No. 100,199.

This invention relates in general to apparatus for supplying oil from a main supply tank to a point where the oil is to be utilized, and more particularly the invention consists in providing apparatus for controlling the supply of fuel oil from a main supply tank to a liquid fuel burner.

One object of the invention is to provide apparatus which pumps or controls the supply of fuel oil from a main tank to an auxiliary tank or reservoir and includes pumps which are sealed by the fuel oil as it flows through the auxiliary tank or reservoir, whereby a simple, inexpensive and reliable reciprocating pump construction may be utilized so that the cost of manufacture and maintenance of the apparatus is low.

Another object is to provide apparatus of the character described which is adaptable for controlling the supply of oil from a main tank which may be either above or below the level of the liquid fuel burner, and which in either case will prevent flooding of the burner by the oil.

Other objects are to provide in such apparatus two series of pumps, one for controlling the supply of oil from the main tank to the auxiliary tank or reservoir and the other for pumping the oil from the auxiliary reservoir to the fuel burner, in combination with valve means controlled by the level of the oil in the auxiliary tank for controlling the supply of oil from the main tank, so that flooding of the fuel burner is prevented and a substantially uniform supply of oil ensured; to provide a pump construction which is adjustable to vary the supply of oil to the fuel burner independently of the flow of oil from the main tank; to provide a novel and improved pump construction and combination thereof with the auxiliary tank or reservoir whereby the various pumping units may be interchangeably used and easily and quickly replaced; to provide novel and improved pump actuating means; to provide apparatus of the character described which is simple and inexpensive in construction and the parts of which are easily accessible for adjustment or repair and which occupies a small amount of space, and to obtain other results and advantages as may be brought out of the following description.

Referring to the accompanying drawings,

in which corresponding and like parts are designated throughout the several views by the same reference characters,

Figure 1 is a top plan view of apparatus embodying the invention with the cover plate removed;

Figure 2 is a longitudinal vertical sectional view taken on the line 2—2 of Figure 1;

Figure 3 is a fragmentary side elevation of the apparatus;

Figures 4 and 5 are transverse vertical sectional views, taken on the lines 4—4 and 5—5, respectively, of Figure 1;

Figure 6 is a transverse vertical sectional view, taken on the line 6—6 of Figure 2;

Figure 7 is a fragmentary sectional view through one of the pumping units and a portion of the auxiliary tank, and

Figure 8 is a transverse vertical sectional view, taken on the line 8—8 of Figure 7.

Specifically describing the illustrated embodiment of the invention, the reference character A designates the auxiliary tank or reservoir which comprises two compartments 1 and 2 disposed in superposed relation and divided by a horizontal wall 3. The upper compartment 2 is preferably removably mounted upon the lower compartment 1 in any suitable manner, as by means of screws 4. The fuel oil is supplied to the lower compartment 1 from the main supply tank (not shown) by a pipe 5, and said main supply tank may be disposed above or below the level of the auxiliary tank A, for instance in the wall of the building or embedded below the floor. The pipe 5 is connected to a valve casing 6 in which is provided an upwardly facing valve seat 7 with which cooperates a ball check valve 8 which normally seats to prevent flow of the fuel oil through the pipe 5. A passage 9 leads from the valve seat 7 through the casing into the lower compartment 1 so that when the valve 8 is unseated the fuel oil may flow into the compartment 1. The end of the passage 9 opposite the valve 8 is provided with a valve seat 10 with which cooperates a valve 11 actuated by a float 12 mounted at one end of a lever 13 pivotally mounted intermediate its ends as at 14 upon the casing 6 and connected at its other end to the valve 11. When a predetermined high level of

fuel oil obtains in the compartment 1 the valve 11 is opened, and said valve is closed by falling of the float 12 when a predetermined low level of fuel oil is reached. The 5 valve 11 carries a push rod 15 for unseating the valve 8 simultaneously with the closing of the valve 11.

Below the normal high level of the oil in the compartment 1, pipes 16 are connected 10 to the valve casing 6 and communicate with the passage 9 intermediate its ends, said pipes being also connected to the inlets of the respective pumping units 17 mounted upon the upper compartment 2. These 15 pumping units preferably comprise substantially rectangular cast metal blocks 18 having two passages 19 and 20 arranged at right angles and communicating with each other, the passages 20 serving as inlets and 20 being controlled by ball check valves 21. The blocks 18 are formed with laterally projecting cylinders 22 the bores of which communicate with the passages 19, and straight cylindrical pistons 23 are reciprocably mounted in said cylinders 22 and project from the outer ends thereof. At the 25 sides of the bores of the cylinders 22 opposite the inlet check valves 21 are arranged outlet check valves 24, and pipes 25 lead 30 from the outlets of the passages 19 into the upper portion of the upper compartment 2, as clearly shown in Figures 1 and 4. The pumping units 18 are secured to the outer sides of the upper compartment 2 by cap 35 screws 26 and the cylinders 22 are inserted through openings 27 in the walls of the said compartment, so that the inner ends of the cylinders are within the compartment; and gaskets 28 are preferably interposed between the blocks 18 and the walls of the 40 compartment 2. With this construction, it will be obvious that movement of the pistons 23 in one direction will serve to draw oil through the inlets 20 into the passages 19, while movement of the pistons in the other 45 direction will force the oil through the outlets 25 into the upper compartment 2. The cylinders and pistons 22 and 23 are thus sealed by the oil within the compartment 2, and accordingly all necessity for the usual 50 packing of pistons is eliminated. The pumping units are extremely simple in construction and are identical with each other, and therefore can be easily and quickly applied to and removed from the apparatus 55 and interchanged.

The pistons 23 are influenced outwardly of the cylinders by helical compression springs 29 and are forced inwardly of the cylinders 60 by actuating mechanism about to be described. It will be noted that the units 17 are arranged opposite each other in spaced relation with their pistons in substantially axial alinement, and an inverted U-shaped rocker 30 is mounted upon a shaft 31 with

one of its arms arranged to engage the end of the corresponding piston 23. An eccentric or cam 32 is on a shaft 33 journaled in bearings 34 in the compartment 2 and disposed substantially equidistantly between the pumping units 17, said cam being arranged between and frictionally engaging the arms of the rocker 30, as clearly shown in Figures 2 and 4. Obviously, rotation of the shaft 33 causes corresponding rotation 75 of the cam 32 which due to its engagement with the arms of the rocker 30 will oscillate the latter about the shaft 31 to alternately force the pistons 23 inwardly of their respective cylinders and permit the pistons to be moved outwardly of their cylinders by the springs 29. The shaft 33 may be driven in any suitable manner, but preferably by a worm wheel 35 meshing with a worm 36 fast on a shaft 37 journaled in bearings 38 80 and disposed at substantially right angles to the shaft 33. The shaft 37 may be connected to any suitable source of power such as an electric motor (not shown). The level of the oil in the upper compartment 2 is 85 maintained at a uniform level above the pump cylinders, the cam 32 and the worm 35 by means of an overflow pipe 39 through which the oil returns to the lower compartment 1. Accordingly, the pumping units 90 are sealed and lubricated by the oil, and similarly the cams 32 and worm gearing 35 and 36 together with the bearings 34 and 38 are also lubricated.

Another pumping unit 40 which is identical with the units 17 is secured to one side of the upper compartment 2 and has its inlet connected by a pipe 41 to the lower compartment 1 above the valve seat 10, as indicated at 42. The outlet of said pumping unit 40 is connected by a pipe 43 to the liquid fuel burner (not shown). This pumping unit is operated by a second rocker 44 mounted on the shaft 31 and oscillated by a cam 45 fast on the shaft 33, so that the oil is pumped from the lower compartment 1 to the fuel burner. The supply of oil to the fuel burner may be regulated by varying the stroke of the pumping unit 40, and this may be accomplished by a suitable slide 46 adjustable by a bolt and slot connection 47 with the bottom of the upper compartment 2 to limit movement of the rocker 44 under the influence of the piston spring of the pumping unit, whereby the outward movement of the piston is limited and consequently the stroke thereof in both directions. It will be clear that the smaller the movement of the piston in each direction the smaller will be the supply of oil to the fuel burner. This pumping unit 40 is oil sealed in the same manner as are the pumping units 17. The ends of the pipes 25 opening into the upper compartment are preferably approximately on a level with the shaft 31 so that the 100 105 110 115 120 125 130

oil as it is discharged from said pipes is splashed upon the shaft and lubricates the bearings.

The operation of the apparatus will in general be understood from the foregoing description. As indicated, the oil from the main tank flows through the pipe 5 to the valve casing 6. In the initial operation of the apparatus, the lower compartment 1 will 5 preferably be filled with oil to the maximum high level and the compartment 2 will be filled to the level of the upper end of the overflow pipe 39. The pumps are actuated by the motor (not shown), cams 32 and 45 10 and the respective rockers 30 and 44, and the oil is pumped from the lower compartment 1 through the inlet passage 9 by the pumping units 17 into the upper compartment 2. The oil overflows downwardly into the lower 15 compartment 1 from where it is pumped by the pumping unit 40 to the fuel burner. Should the level of oil in the compartment 1 reach a predetermined low limit, the float 12 will close the valve 11 and open the valve 20 8 by the rod 15, whereupon the oil will flow by action of gravity through the pipe 5 if the main tank is above the level of the compartment 1, or will be pumped from the main tank by the pumping units 17 if the 25 tank is below the level of the compartment 1. This action will continue until sufficient oil has overflowed from the compartment 2 into the compartment 1 to raise the level of the oil in the lower compartment to its pre- 30 determined high level when the valve 8 will be closed and the valve 11 opened. It will be understood from the foregoing that the oil is taken from the lower compartment 1 or directly from the supply pipe 5, according 35 to the level of the oil in the reservoir. The level of the connection 42 of the pumping unit 40 to the lower compartment is preferably above the level of the valve 11 so that said valve will be oil sealed and prevent air 40 from entering the pipes 16 and pumping units 17 in such a manner as to interfere 45 with the operation thereof.

With this construction, the moving parts of the apparatus are effectively lubricated and the pumping elements oil sealed by the oil being pumped. The moving elements are in a separate compartment from that containing the oil which is directly pumped to the fuel burner. Furthermore, all parts 50 are easily accessible, and the superposed relation of the two compartments provides a compact device which may occupy a small area of floor space.

While I have shown and described the 55 invention as embodying certain details of construction, it will be understood that this is primarily for the purpose of illustrating the principles of the invention and that many modifications and changes may be 60 made in the details of construction by those

skilled in the art without departing from the spirit and scope of the invention. Therefore, I do not desire to be understood as limiting myself except as required by the following claims when construed in the light of the prior art.

Having thus described the invention, what I claim is:

1. Apparatus of the character described comprising a reservoir for oil, a pump including an unpacked cylinder and piston arranged in said reservoir so that said cylinder and piston are sealed by the oil in said reservoir, said pump having an inlet to be connected to an oil supply and an outlet 75 discharging into said reservoir, a second pump including an unpacked cylinder and piston arranged in said reservoir and sealed by the oil therein, said second pump having an inlet connected to said reservoir for withdrawing the oil therefrom and an outlet 80 for delivering said oil to a desired point.

2. Apparatus of the character described comprising a reservoir for oil having an inlet, a check valve arranged in said inlet and normally closed to prevent flow of oil into said reservoir, a float in said reservoir, means actuated by said float to open said valve when a predetermined low level of oil obtains in said reservoir, a second valve in 95 said inlet actuated by said float and open while the level of oil remains above said low limit, said valve being automatically closed when said low level obtains, and a pump having an inlet connected to the inlet 100 of said reservoir between said valves so that while the oil remains above said predetermined low level the pump withdraws the oil from said reservoir while when the oil is at said low level the pump withdraws oil 105 directly from said inlet.

3. The apparatus set forth in claim 2 in which the second-mentioned valve is arranged below said predetermined low level so that said valve is sealed by said oil in 110 the reservoir.

4. Apparatus of the character described comprising a reservoir for oil having two compartments, an inlet for one of said compartments, a check valve arranged in said inlet and normally closed to prevent flow of oil into said compartment, a float in said compartment, means actuated by said float to open said valve when a predetermined low level of oil obtains in said compartment, 115 a second valve in said inlet actuated by said float and normally open while the level of oil remains above said low limit, said valve being automatically closed when said low level obtains, a pump arranged in the other 120 of said compartments, said pump having an inlet connected to said inlet of the first-mentioned compartment between said valves and an outlet communicating with the second compartment, an overflow pipe for the 125 130

second compartment communicating with the first mentioned compartment to maintain the oil in the second compartment at a uniform level above said piston and cylinder of said pump so that the latter are oil sealed, and a second pump in the second compartment and sealed by the oil therein, said second pump having an inlet connected to the first mentioned compartment to withdraw oil therefrom and an outlet to deliver said oil to a desired point.

5. Apparatus of the character described comprising a reservoir for oil having an inlet to be connected to an oil supply, a float 10 in said reservoir, a valve in said inlet actu-

ated by said float and open while the level of oil remains above a predetermined low level, said valve being automatically closed when said low level obtains, and a pump having an inlet connected to the inlet of said reservoir between said valve and the oil supply and an outlet connected to said reservoir, so that while the oil remains above said predetermined low level the pump withdraws the oil and returns it to said reservoir in a circuit, while when the oil is at said low level the pump draws oil directly from the oil supply into said reservoir. 25

GEORGE H. MESSER.
